UNITED STATES PATENT OFFICE.

BARTHOLOMEW GOMMENGINGER, OF ROCHESTER, NEW YORK.

IMPROVEMENT IN HOT-AIR FURNACES.

Specification forming part of Letters Patent No. 116,701, dated July 4, 1871.

To all whom it may concern:

Be it known that I, BARTHOLOMEW GOMMENGINGER, of the city of Rochester, in the county of Monroe and State of New York, have invented a certain new and useful Improvement in Furnaces, of which the following is a specification:

This invention consists in combining, with the hot-air chamber of the furnace, a system of hot-water pipes, by which the heat in said chamber is equalized and increased.

In the drawing, Figure 1 is a horizontal section of my furnace through the water-jacket; Fig. 2, a central vertical section; Fig. 3, a view showing the rings of the water-jacket; Fig. 4, a plan of the ash-pit and its extension, showing more particularly the register for the admission of air to the fire.

A is the outer and B the inner wall of the furnace, the latter inclosing the hot-air chamber C, from which the heat is distributed. D is the fire-pot; E, the grate; and G the ash-pit, having an extension, H, which extends out through the walls in the usual way. Through the top of this extension is made a series of draught-holes, *a a*, within the hot-air chamber, and these holes are covered by sliding in the register *b*, which has a stem extending outside the furnace-walls. The walls of the ash-pit are made hollow, to form a water-jacket, I. This jacket may be made in a single chamber, as in Fig. 2, or in the form of two or more rings, I I', as in Fig. 3, in which case they are placed one on top of another loosely, each ring being independent from its fellows, and each having a system of pipes extending through the hot-air space, as will presently be described. In furnaces of large size and capacity it may be desirable to construct the water-jacket in separate rings in this way, and the furnace may thus be built up to meet the requirements of the case. By placing it in the walls of the ash-pit and sinking the grate therein, as shown, a very large water-surface is attained, and the fire comes in direct contact therewith. With each ring of the water-jacket is connected a complete system of pipes, K K', which circle in any desired manner through the hot-air chamber all around the furnace proper. These pipes start from the top of each ring, as shown at *d*, and, after making the

circuit, return at the bottom, as shown at *f*, thus insuring a complete and constant circulation of the water. The object of this arrangement is to increase and equalize the heat in the air-chamber C by extending the coils in all directions. A great difficulty in common furnaces is that the radiation is principally opposite the fire-pot and the lower part of the furnace, which gives an unequal temperature. The hot-water pipes by permeating every part cause an even and uniform temperature. If desired, the hot-water pipes may be extended beyond the furnace, and made to heat distant rooms. The pipes are connected with a water-tank, L, by means of branch pipes *g h*, the former of which furnishes the supply, while the latter serves simply as an exhaust-pipe for the steam. This tank serves as a fountain to the water-jacket, and also as a warm-water tank for ordinary use. A steam-cock, *k''*, is connected with the pipes inside the air-chamber, and employed to inject steam into the hot air for the purpose of moistening it. It is common to use water-basins for the purpose of evaporation.

The draught-air for supporting the combustion is drawn directly from the hot-air chamber or space C, through the holes *a* or any equivalent flue-passage, as such air combines readily with the fire, and, by its burning, prevents the forming of clinkers, which is a great difficulty in heating-furnaces. There is also a great saving of fuel, as the air is warmed before it reaches the fire. In this manner a perpetual fire is sustained.

What I claim, and desire to secure by Letters Patent, is—

1. Constructing the water-jacket in two or more separate rings, capable of being placed one upon another, and each having a separate system of pipes, in the manner and for the purpose specified.
2. The combination of the water-jacket I, water-pipes K K', steam-cock K'', branch pipes *g h*, and water-tank L, substantially as and for the purpose set forth.

B. GOMMENGINGER.
